UNITED STATES PATENT OFFICE.

FREDERICK J. WALLACE, OF BUFFALO, NEW YORK.

DESIGN FOR A STICK-PIN.

SPECIFICATION forming part of Design No. 31,115, dated July 4, 1899.

Application filed April 4, 1899. Serial No. 711,744. Term of patent 3½ years.

To all whom it may concern:

Be it known that I, FREDERICK J. WALLACE, a citizen of the United States, residing at Buffalo, in the county of Erie and State of New York, have invented and produced a new and original Design for a Stick-Pin or Similar Article, of which the following is a specification.

This invention relates to a new and original design for a stick-pin or similar article; and it has for its object to provide a design of this character that shall be both useful and ornamental.

The leading feature of the design resides in a stick-pin having the body thereof approximating the outlines or configuration of a dust-pan and bearing the representation of an American buffalo.

In the drawing the figure is a perspective view of a stick-pin embodying the herein-described design.

Referring to the accompanying drawing, the numeral 1 designates the body of a pin or similar article which, as shown in the drawing, approximates the outlines or configuration of a

dust-pan of an approximately U shape and 25 provided with a single offstanding arm 2, projected from the rounded side at the upper edge thereof. The said pan-shaped body 1 is provided upon the obverse side thereof with the representation of an American buffalo, 30 and the said single offstanding arm 2 at the top edge of the body is provided with an opening 3 and is connected with a terminal hook 4 at the upper end of a straight pin 5. The pan-shaped body associated with the representation of the American buffalo is symbolical of the Pan-American consolidation.

What is claimed is—

The design for a stick-pin or similar article, 40 herein shown and described.

In testimony that I claim the foregoing as my own I have hereto affixed my signature in the presence of two witnesses.

FREDERICK J. WALLACE.
